UNITED STATES PATENT OFFICE.

FRANK A. YOUNG, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,060,806.

Specification of Letters Patent.

Patented May 6, 1913.

Application filed June 29, 1910. Serial No. 569,510.

To all whom it may concern:

Be it known that I, FRANK A. YOUNG, a citizen of the United States, residing in New York, in the county of New York and State of New York, have invented certain new and useful Improvements in Type-Writing Machines, of which the following is a specification.

This invention relates to the ribbon mechanism in that class of typewriting machines in which the ribbon is vibrated to cover and uncover the printing point at each type stroke, and in which the ribbon is wound by means of the spring or motor which drives the letter-feeding carriage of the typewriting machine.

In United States patent to Frank A. Cook, No. 926,050, granted June 22, 1909, is shown a special lever for silencing the ribbon vibrator, so that the types may print off the ribbon when required, as in making stencils.

According to the present invention, the ribbon-winding devices are connected up to the carriage-driving spring-barrel in a manner to permit the ribbon-winding mechanism to be simultaneously silenced, so that the ribbon lies entirely dead at the key strokes, as when stenciling.

In carrying out this invention, the spring-barrel is caused to drive a worm, which meshes with a worm wheel that is provided upon a main ribbon-winding shaft, the latter being movable endwise to connect with either and disconnect from the other ribbon-spool shaft. The worm-wheel is lengthened to form a barrel pinion, so that the worm may always remain in mesh therewith, notwithstanding the endwise shifting of the main ribbon-winding shaft. The lever which silences the ribbon vibrator is also connected to a device to lift said worm away from the worm-wheel, so that, although the worm continues to revolve while the carriage feeds, the worm-wheel and the shaft remain motionless.

Other features and advantages will hereinafter appear.

In the accompanying drawings, Figure 1 is a plan of a portion of the well-known Underwood front strike writing machine, with the present improvements applied thereto. Fig. 2 is a perspective view, show-

ing the main ribbon-drive shaft and its connections, particularly the means whereby it is silenced; the members being shown in 55 normal positions. Fig. 3 is a front view of parts seen at Fig. 1; showing the ribbon vibrator as silenced, and the ribbon-winding mechanism as also silenced. Fig. 4 is a cross-section of the main transverse ribbon-driving shaft, showing a worm wheel and ratchet mechanism. Fig. 5 is a similar view to Fig. 3, but showing the parts in normal operative positions. Fig. 6 is a sectional side elevation of the worm shaft and the 65 devices whereby it is connected to the carriage-driving spring-barrel. Fig. 7 is a sectional side elevation of the ribbon-actuator and the connected lever and ribbon vibrator; these parts shown in normal positions. 70

The inking ribbon comprises color fields or stripes 1, 2, through which types 3 strike rearwardly against a platen (not shown). The ribbon is threaded through a vibrator 4, which is operated by a lever 5, the latter 75 pivoted at 6 upon a bracket 7, secured to a shift rail 8 of the capital or case-shifting mechanism in said machine.

A universal bar 9, vibrated by the type bars, is fixed upon a frame 10. Carried 80 upon said frame 10 is an actuator 11, having one vertical slot 12 to engage a wrist 13 upon the lever 5, and an opposite vertical slot 14 to engage a wrist 15 provided upon said lever nearer to the fulcrum 6 of the 85 lever. Said slots are formed in ears bent forwardly from the body of the actuator, and the latter is adjustable to bring either slot into engagement with its associated wrist, such adjustment being effected by a 90 link 17 pivoted at 18 to the actuator, and the latter being held by screws or rivets 19 upon a bracket 20, fixed upon said universal bar frame 10; the vertical wall of said bracket having a horizontal slot 21 through 95 which said screws extend, the slot permitting the required adjustment of the actuator.

When the slot 12 is in engagement with wrist 13, the lever 5 is given a short stroke, and the upper stripe 1 is caused to cover 100 the printing point at the type strokes. When, however, the actuator is shifted to bring the slot 14 into engagement with the wrist 15, the lever 5 is given a greater

stroke at the type strokes, and hence the lower stripe 2 is caused to cover the printing point. For effecting this adjustment of the actuator, the link 17 is connected to an arm 22, fixed upon a rock shaft 23, the latter carrying at its forward end a cross-arm 24, having keys 25, 26, corresponding to the stripes 1, 2, so that, upon the depression of either key, the corresponding stripe or color band is brought into use.

10 A yielding detent 27 is caused to engage the beveled end of a pin 28, projecting rearwardly from arm 24 to hold said arm either in the position at Fig. 5 or in a reverse position, to cause either stripe 2 or stripe 1 to cover the printing point of the type strokes; said detent 27 being incapable of holding the train 24, 23, 22, 17 and 11 in a midway position.

20 Pivoted to the framework 30 of the machine at 31 is a lever 32, having at its upper end a handle 33. Between its ends it is provided with a transverse slot 34, whose open end terminates in opposite cams 35, 36, so constructed that when the lever is moved to the left, said projection 28 is engaged by either one or the other of said cams 35, 36, and the key-bearing cross lever 24 is brought to the horizontal position 30 at Fig. 3; the entire train of devices thus being brought to a position midway of its extreme positions, and both wrists 13 and 15 being out of engagement with the slotted actuator 11, so that the latter, although reciprocating at the type strokes, has no effect upon the ribbon-vibrating lever 5, and hence the ribbon is silenced, and the type strikes above or off from the ribbon as at Fig. 3. The sides of the slot 34 are of such shape, 40 as to lock the key-bearing cross lever 24 against movement while said lever is in the Fig. 3 position. At this time the detent 27 rests idly upon the tip of the tooth 28, Fig. 1.

45 As so far described in detail, the parts are found in said Patent No. 926,050. It will be understood, however, that the present improvements may be applied, in some cases, to machines in which a bichrome ribbon or 50 a bichrome mechanism is not used.

The ribbon 1, 2, is carried upon spools 40, one at each side of the printing-point, and mounted upon a pair of vertical shafts 41, carrying at their lower ends bevel pinions 55 42, 43, to mesh with bevel pinions 44, 45, fixed upon a transverse horizontal drive-shaft 46, which may be shifted endwise to cause either spool shaft 41 to wind. At Fig. 1, the pinion 44 is shown engaged with 60 41; but by moving the shaft 46 to the right, said pinions are disengaged, and 45 is moved into mesh with 43, thus causing the direction of winding of the ribbon to be reversed. Upon the shaft is fixed a double-bevel collar 65 47, to be engaged by a pointed spring de-

tent 48, for holding shaft 46 at either end of its endwise movement. Said shaft may carry upon its end a winch 49.

Upon the shaft 46 is a barrel pinion 50, with which meshes a worm 51, upon a horizontal shaft 52, which extends rearwardly and at its rear end connects, by means of a pinion 53, with a gear 54, which is fixed upon a spring barrel 55, the latter connected by a strap 56 to the paper carriage, a portion of which is seen at 57. During the rotation of the spring barrel, the gear 54 turns the pinion 53, the shaft 52, and the worm 51, and the latter rotates the barrel-pinion or worm-wheel 50, thereby revolving the ribbon-driving shaft 46 and either one or the other ribbon-spool shafts 41. The barrel pinion 50 is loose upon the drive-shaft 46, and it is formed with a ratchet wheel 58, with which is engaged a spring 85 pawl 59, pivoted upon a disk 60, which is formed upon a hub 61 of the pinion 44, said hub being secured to the shaft by a screw 62, thus permitting the shaft 46 to be rotated manually by the winch 49, while the 90 pinion 50 is in mesh with the worm 51.

In order to enable the carriage to return to the beginning of a new line without turning the worm shaft 52, a ratchet 62 is fixed upon said shaft 52, and engaging therewith 95 is a spring pawl 63 pivoted upon a disk 64, which is rigid with the pinion 53, both 53 and 64 being loose upon the shaft 52. Backward turning of shaft 52 is prevented by a gravity pawl 65, engaging a ratchet-wheel 66 100 fixed upon the shaft 52. It will be seen that the worm 51 remains in engagement with the pinion 50 during endwise shifting of the shaft 46. Said barrel pinion is confined between the disk 60 and the collar 47, 105 the latter having a hub 67 secured to the shaft by a screw 68.

The ribbon-winding mechanism is silenced by lifting the worm 51 from the worm wheel or pinion 50. To this end, the shaft 52 is 110 prolonged forwardly from such worm, and is loosely mounted at its forward end at 69 in one end of a lever 70, which is pivoted between its ends at 71, and carries at its other end a cam 72, engageable by a pin 73 projecting from the lever 32, so that, as the latter is swung from the normal position at Fig. 5 toward the left to the effective position at Fig. 3, the pin 73, by reason of its engagement with the cam 72, forces the lever 115 70 to vibrate, carrying up the shaft 52 and releasing the worm 51. The shaft 52 is loosely pivoted at its rear end in a support 74, Fig. 1, to permit the forward end of said shaft to be rocked up as described. Said 120 cam 72 terminates in a dwell portion 75, which is engaged by the pin 73, whereby the lever 70 is mechanically held in the silencing position seen at Fig. 3; so that both the ribbon-vibrating and the ribbon- 130

winding devices are silenced during the type strokes, for stenciling, etc. Upon returning the lever 33 to the right, to normal position, the lever 24 is released, and the lever 70 is 5 returned to normal position by means of a spring 77, Fig. 2, or by gravity, thus restoring the engagement of the worm 51 with the pinion 50. Thus it will be seen that at any time either key 25 or 26 may be depressed 10 to bring either stripe of the ribbon into use; and any time the lever 33 may be swung to the left to silence both the ribbon-vibrator and the ribbon-winding devices.

Having thus described my invention, I 15 claim:

1. In a ribbon movement, the combination with a carriage-driving spring and ribbon spools, of a shaft, a worm mounted on the shaft, driving means between said spring 20 and shaft, a gear co-acting with said worm, means to connect said gear with said spools alternately, and means for moving said shaft transversely to its length to unmesh said worm from said gear.
2. In a ribbon movement, the combination with a carriage-driving spring and ribbon spools, of a shaft, a worm mounted on the shaft, driving connections between said spring and shaft, a gear meshing with said 25 worm, means to connect said gear with said spools alternately, and a lever provided with a bearing for one end of said shaft to move the worm out of mesh with said gear.
3. In a ribbon movement, the combination 30 with a carriage-driving spring and ribbon spools, of ribbon-feed reversing means, a worm and gear interposed between said spring and spools, driving connections between said spring and worm, said gear being endwise or axially shiftable at the operation of reversing the ribbon feed, and of such length and position as to remain in mesh with said worm during such endwise shifting, and means for separating the 35 worm and gear, to silence the ribbon.

4. In a typewriter ribbon movement, the combination with a carriage-driving spring drum, of a shaft driven by said drum, a worm on said shaft, a gear with which said 40 worm is normally in mesh, a lever provided with a bearing for said shaft, ribbon-spools driven from said gear, a ribbon-vibrator, a second lever, and connections whereby said second lever renders said vibrator 45 inactive and moves the first lever to unmesh said worm and gear.

5. In a typewriter ribbon movement, the combination with ribbon-spools, of an endwise shiftable shaft, gearing whereby said 50 shaft drives said spools one at a time, a long gear or pinion fast on said shaft, a worm meshing with said long gear in all adjustments of the latter, and means to separate said worm and said long gear.

6. In a typewriter ribbon movement, the

combination with the ribbon spools, of an endwise movable long gear, connections whereby said gear operates said spools, a worm for driving said gear and remaining in mesh therewith during the endwise shifting thereof, and means for moving said worm out of mesh with said gear.

7. In a typewriter ribbon movement, the combination with the ribbon spools, of an endwise movable long gear, connections 70 whereby said gear operates said spools, a worm for driving said gear and remaining in mesh therewith during the endwise shifting thereof, a shaft carrying said worm and movable to carry said worm into and out of mesh with said gear, and a lever connected with said shaft to move the same.

8. In a typewriter ribbon movement, the combination with the ribbon spools, of an endwise movable long gear, connections 75 whereby said gear operates said spools, a worm for driving said gear and remaining in mesh therewith during the endwise shifting thereof, a shaft carrying said worm, a lever provided with a bearing for said shaft, whereby said worm may be moved into and out of mesh with said gear, and a second lever for operating said shaft moving lever.

9. In a typewriter ribbon movement, the combination with the ribbon-spools, of an endwise movable long gear, connections 80 whereby said gear operates said spools, a worm for driving said long gear, a shaft carrying said worm, a lever provided with a bearing for said shaft, whereby said worm may be moved into and out of mesh with said gear, a ribbon-vibrator mechanism, a second lever, and connections from the latter for simultaneously operating said shaft-moving lever to unmesh said worm and gear and for silencing said ribbon-vibrator mechanism.

10. In a typewriter ribbon movement, the combination with ribbon spools, of a carriage-driving spring drum, a shaft geared at one end to said drum to be driven thereby, means for moving transversely the end of said shaft not geared to said drum, a second shaft having a gear in mesh with a gear on the first shaft, said gears being separable by the transverse motion of the first shaft, and a pair of ribbon spool shafts connectible alternately to said second shaft.

11. In a typewriter ribbon movement, the combination with the carriage driving spring drum, and the ribbon spools, of a shaft geared at one end to said drum to be rotated thereby, a lever in which the other end of said shaft is journaled, gearing interposed between said shaft and said spools for driving said spools one at a time and having two members which are unmeshed from each other by the movement of said shaft by said lever, a ribbon vibrator, vi- 120 125 130

brator mechanism having disconnectible members, a hand lever, and connections whereby said hand lever operates simultaneously said shaft moving lever and said disconnectible members.

12. The combination of a pair of ribbon spools, a drive shaft shiftable endwise to connect with either spool, a gear on said drive shaft, a worm in mesh with said gear at either position to which the latter is shifted, means for rotating said worm, and means for effecting separation between said worm and said gear.

13. The combination of a pair of ribbon spools, a drive shaft shiftable endwise to connect with either spool, a gear on said drive shaft, a worm in mesh with said gear at either position to which the latter is shifted, a shaft on which said worm is mounted, a carriage-driving spring barrel connected to said shaft, and means to move said worm shaft to effect separation between said worm and said gear.

14. The combination of a pair of ribbon spools, a drive shaft shiftable endwise to connect with either spool, a gear on said drive shaft, a worm in mesh with said gear at either position to which the latter is shifted, a shaft on which said worm is mounted, a carriage-driving spring barrel connected to said shaft, and a lever on which said worm shaft is journaled, and whereby it is shiftable to disengage the worm from the gear.

15. The combination of a pair of ribbon spools, a drive shaft shiftable endwise to connect with either spool, a gear on said drive shaft, a worm in mesh with said gear at either position to which the latter is shifted, means for rotating said worm, a ribbon vibrator, means for silencing said vibrator, and a connection from said silencing means to said worm to disengage the latter from said gear.

16. In a typewriter ribbon movement, the combination with the ribbon spools, of an endwise movable long gear, connections whereby said gear operates said spools, a

worm for driving said gear and remaining in mesh therewith during the endwise shifting thereof, a shaft carrying said worm, and a lever, provided with a bearing for said shaft, whereby said worm may be moved into and out of mesh with said gear.

17. The combination of a carriage-driving spring, a ribbon-winding mechanism connected thereto, a ribbon vibrating mechanism, a finger-piece, means controlled by said finger-piece for varying the throw of said vibrating mechanism, and a locking lever operable to hold said finger-piece in a neutral position and disconnect the ribbon-winding mechanism for concomitantly silencing said vibrating mechanism and said winding mechanism.

18. In a typewriting machine, the combination of ribbon feeding mechanism, a ribbon vibrator, an operating lever, means for actuating the same including a link connected to the lever, said link and lever being relatively movable to vary the distance between the link and the lever fulcrum without varying the throw of the lever, a device for changing the positions of said link to vary the throw of the vibrator and to disconnect the link to render it when actuated inoperative to move said lever and said vibrator, and means connected with said device to render said ribbon feeding means inoperative when said link is inoperative.

19. In a typewriting machine, the combination of ribbon feeding mechanism, a ribbon vibrator, an operating lever therefor, a universal bar, a link connected directly to said universal bar and movable in either direction from a neutral intermediate position to connect it to said operating lever, a device for moving said link to its neutral position to disconnect it from said operating lever, and means connected to said device for rendering said ribbon feeding means inoperative.
